(57) **CLAIM**

The ornamental design for a housing for electrical connector, as shown and described.

DESCRIPTION

The present application is related by subject matter to design patent applications entitled "Electrical Connector" filed on even date herewith under U.S. Design application Ser. No. 29/393,276, pending, and "Electrical Connector" filed on even date herewith under U.S. Design application Ser. No. 29/393,280, pending.

FIG. 1 is a top, right, front perspective view of a housing for electrical connector according to my design;

FIG. 2 is a bottom, left, rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken line portion of the figure drawings is included to show unclaimed subject matter only and forms no part of the claimed design.

In a preferred embodiment, the nature of this product is a housing for supporting electrical terminals of an electrical connector that are configured for electrically connecting to an electrical device.
